UNITED STATES PATENT OFFICE.

JOHN H. POCOCK, OF CHICAGO, ILLINOIS.

COAL-HOD.

Specification forming part of Letters Patent No. 59,925, dated November 20, 1866.

To all whom it may concern:

Be it known that I, JOHN H. POCOCK, of the city of Chicago, in the State of Illinois, have invented a certain new and useful Improvement on Coal Hods or Scuttles; and I do hereby declare that the following is a full, clear, and exact description thereof, reference being had to the accompanying drawings, and to the letters and marks therein.

The drawings, which form part of this specification, represent a hod or scuttle constructed under my invention, Figure 1 thereof being a top view of the scuttle, or a view had by looking down upon it; and Fig. 2, a view by longitudinal section.

In both of these figures like marks and letters are used to indicate like parts.

This scuttle differs from those now in general use, first, in the formation of the lips *a*, which are so constructed that the coal cannot in any case get out of the scuttle when feeding the stove except through the spout, the lips being so formed that when the coal is passing out and the scuttle being emptied, the spout will form, in connection with the feeding hole or door of the stove, a perfect chute or channel. The lips extend back to the center of the hod, thus affording greater capacity than any other hod now in use; and the sides and lips being of one piece of metal gives an advantage in the manufacture of the hod, and saves both time and money.

This scuttle differs, secondly, from others in general use in the construction of the bottom, which, as is fully shown by Fig. 2 of the drawings, is made of two pieces, *b* and *c*, the one piece, *b*, being of concave shape and swaged into form, with a flange for its attachment to the body of the scuttle, and the other piece, *c*, being also concave and swaged into form, with a flange that becomes the bottom bearing-surface of the scuttle.

The drawings show the two pieces *b* and *c*

connected by rivets; but they may be connected, as may also the piece *b*, to the scuttle's body by any other means commonly used for attaching plates of metal to each other.

The bottom, being stamped or swaged, and of two thicknesses of metal and concave, is superior to scuttles of one thickness of metal for the bottom, and of other forms having less ability to resist weight or pressure.

This scuttle is much stronger, the expense of manufacture not increased, and, the bottom hoop and outside bottom piece being stamped or swaged out of one piece of metal, less material is used than in the usual way of cutting out the pieces separately and making up the bottom from the several pieces.

When finished and painted or coated with the material or mixture commonly used for covering or painting scuttles, this hod or scuttle will be water-tight, so that if the coal is wet leakage will not occur.

I do not claim forming the bottom of one piece of metal cut out and swaged into form; but

What I do claim as my invention, and desire to secure by Letters Patent, as an improvement on coal hods or scuttles, is—

1. The bottom made up of the pieces *b* and *c*, the pieces having the flanges for connection to the body of the scuttle, and for forming the hoop or bottom bearing-surface as a part of them, and constructed substantially as herein set forth.

2. The lips *a*, when constructed and formed, as herein recited, with the side pieces of the scuttle, as described.

This specification signed this 25th day of September, 1865.

JOHN H. POCOCK.
